APPARATUS FOR MANUFACTURING
METAL CLOSURESBert J. Huntsman, Wheeling, W. Va., assignor
to Hazel-Atlas Glass Company, Wheeling,
W. Va., a corporation of West Virginia

Application October 24, 1934, Serial No. 749,855

9 Claims. (Cl. 153—7)

The invention relates to a machine for threading, beading and knurling metal blanks or shells, to form screw caps; and particularly to the manufacture of such caps having relatively deep threads.

In the old conventional cap threading machines the thread and the bead are formed simultaneously; and consequently when relatively deep threads are formed there is a tendency to stretch the metal, which sometimes results in breaking or splitting the threads. This happens because the metal is gripped at one end by the knurling tools and at the other end by the bead curling tools, so that the metal is not free to flow in forming the deep threads. In the machine constituting the present invention the skirt of the blank is free while the threads are being formed, whereby the skirt can freely shrink while the deep threads are rolled. Heretofore several machines have been suggested in which the skirt of the blank is free while the thread is being rolled, but such machines are either very complex or involve rather expensive changes in the present conventional equipment. One of the objects of the present invention is to provide a machine of this character which requires only a slight change in the conventional threading equipment.

A further object of the invention is to provide a very simple cap threading machine of the character described above, in which it is possible to easily and quickly reverse the order of operation, so that the threads may first be formed, followed by the forming of the bead, or the bead may first be formed followed by the forming of the threads.

Another object of the invention is to provide a threading machine of the character described, which eliminates the tendency of the tool to slip on the shell, with a consequent disfiguration of the shell coating.

Still another object of the invention is to provide a device of this character in which the thread grooves will exactly match at all times, thereby eliminating the kink or bump which is sometimes formed in caps where the thread overlaps, when using the conventional threading machines.

Various other objects and advantages of the invention will be apparent to those skilled in the art from the following detailed description, when taken in connection with the accompanying drawings, in which:

Figure 1 is a fragmentary view, partly in section, of the cap forming machine, and showing

the tools in inoperative position, and with a hat-shaped blank mounted on the male chuck.

Figure 2 is a view similar to Figure 1 but with the tools moved to operative position and forming the thread on the blank, while the flange on the blank remains free.

Figure 3 is a similar view but showing the thread completed and the bead being formed.

Figure 4 is a detail front view of the beading ring removed from the machine.

Figure 5 is a similar view of the threading ring removed from the machine; and

Figure 6 is a side elevational view of the threading ring.

Referring to the drawings in more detail, numerals 1 and 2 refer to the usual spindles of the conventional threading machines. These spindles are mounted for rotation and are relatively movable toward and from each other. The means for rotating these spindles in synchronized relation, and the means for relatively moving the spindles toward and from each other, are old and well known, and per se form no part of the present invention. Accordingly it is unnecessary to illustrate these means.

Keyed or otherwise removably secured to the spindle 1 are the male threading ring 3, knurling ring 4 and curling ring 5. A blank or shell 6, preferably hat-shaped, is placed on the male chuck by any suitable feeding device or by hand, and a rotatably mounted disc 7 is moved forward to engage the top of the blank to hold the latter firmly in place during the forming operations.

All of the apparatus thus far described is old and well known in conventional threading machines. Such machines also include knurling, threading and curling rings mounted on the spindle 2. Such rings are quite similar to the rings 3, 4 and 5 shown mounted on spindle 1. The knurling rings on spindles 1 and 2, of the conventional threading machines, are of the same diameter, and the threading ring on spindle 2 is therefore of slightly greater diameter than the threading ring on spindle 1, so that when a complete revolution has been made the thread grooves in the threading rings will not match the thread already rolled in the cap, with the result that a kink or bump is often formed in the cap thread at the point where the thread overlaps.

Also in the conventional threading machines, the curling ring is provided with a groove throughout its entire circumference, to receive the flange on the hat-shaped blank and curl it

into the finishing bead. Thus when the male and female chucks are laterally moved relatively to bring them into operative relation, all three of the rings, i. e., the knurling, threading and curling rings, come into play simultaneously, and the knurl, the thread and the bead are formed simultaneously. This simultaneous forming action has two disadvantageous results. First, as the metal is gripped by the curling rings in the beading operation the skirt is not free to shrink while the thread is being rolled, and if deep threads are being rolled the metal is stretched so that breaking or splitting of the threads sometimes results; and second, due to the simultaneous formation of the knurl, thread and bead, considerable pressure is required, and consequently there is a pronounced tendency of the tools to slip on the shell, whereby some of the coating or finish is torn from the shell.

20 All of the above mentioned and other disadvantages of the conventional threading machine are eliminated by a slight and inexpensive change, as will now be described.

In the machine constituting the present invention both the male and female chucks revolve at the same peripheral speed, as is the case in the conventional machines, but in accordance with the present invention the diameter of the female chuck is made larger than the diameter of the male chuck by such an amount that when the female chuck has made part of one revolution the male chuck has turned enough to cause the desired amount of thread to be rolled; and the thread having been completed the curling rings 35 then come into play and form the bead.

The construction will be more clearly understood by reference to the drawings. Keyed or otherwise removably secured to the spindle 2 are knurling ring 8, threading ring 9 and curling ring 40 10. The threading ring 9 is provided with the desired thread 9', and this thread extends only part way around the threading ring, about half way around it in the specific form illustrated. It will be understood, however, that the diameter 45 of the female threading ring is considerably greater than that of the male threading ring, so that when the female threading ring has made about a half revolution, in the specific form illustrated, the male threading ring will have rotated 50 sufficiently to complete the thread.

The thread has been completed during the half turn of the female chuck, and during this time the flange 6' of the blank 6 has been entirely free, as it has been travelling in a cut-out portion 10' 55 of the curling ring 10, as clearly shown in Figure 2; and hence the skirt of the blank has been free to shrink while the thread was being rolled, thereby permitting the rolling of deep threads without stretching the metal. Upon completion 60 of the thread the curling groove 10'' comes into play and forms the bead. This curling groove 10'' extends about half way around the curling ring 10, and as clearly shown in the drawings the curling ring and the threading ring are oppositely arranged, so that substantially one half of the circumference of the female chuck is threaded and the opposite half of the circumference comprises the curling groove 10''. The thread 65 and bead having been formed as above described, the male and female chucks are moved laterally apart to permit removal of the completed cap; the diameter of the completed cap being greater than that of the male chuck in accordance with conventional practice, to permit easy removal.

70 75 While I have described the threading action as

preceding the curling action, it will be understood of course that the bead can be formed first, followed by the formation of the thread; it being only necessary to shift the threading and curling rings through 180° on the spindle 2, and by reference to Figures 4 and 5 it will be noted that diametrically opposed keyways are provided for that purpose. No particular description of the knurling operation has been given, as it remains substantially the same as in the conventional threading machines. The diameter of the knurling ring 8 on spindle 2 is, of course, considerably greater than the similar knurling ring of the conventional machines, but their actions remain substantially the same.

15 From the foregoing description it will be understood that the only change necessary in the conventional threading machine is to make the female chuck larger than the conventional female chuck, so that the threading operation can be 20 completed during partial rotation of the female chuck and the beading operation performed during another portion of the rotation.

By reason of this simple change in structure it is possible to roll deep threads without danger 25 of stretching and breaking the metal, for the skirt of the blank or shell is entirely free to shrink while the thread is being rolled. Also, this slight change in structure permits the threading and curling operation to be reversed, 30 so that the blank can be threaded first and the bead then formed, or the bead formed first and followed by the threading operation. Further, the slight change in the conventional threading machine disclosed herein eliminates the slipping 35 of the tools on the blank or shell, with the consequent disfiguration of the coating; for the threading and beading operations being performed consecutively, though in the desired order, so great a pressure of the tools is not necessary as in the case of the conventional machines where the threading and curling operations are performed 40 simultaneously. Also, the slight change disclosed herein causes the threading grooves to exactly match at all times, thereby eliminating the kink 45 or bump which often occurs where the thread overlaps on the cap, when the threads are rolled on the conventional machines.

It is to be particularly noted that all of these advantages are accomplished without requiring 50 any new equipment, except new rings on the female chuck, and consequently the expense involved is extremely slight.

Having fully described the invention, what I claim is:

55 1. A machine for threading and beading metal caps, including two rotatable chucks, said chucks being relatively movable laterally into operative position, knurling, threading and curling rings provided on each of said chucks, said rings on one chuck being of greater diameter than the rings of the other chuck, a thread on the larger threading ring extending substantially halfway around its circumference, a curling groove in the larger curling ring and extending substantially halfway around its circumference, said thread and said groove being oppositely disposed.

2. A machine for threading and beading metal caps, including two rotatable chucks, said chucks being relatively movable laterally into operative 70 position, knurling, threading and curling rings provided on each of said chucks, said rings on one chuck being of greater diameter than the rings of the other chuck, a thread on the larger threading ring extending substantially half way 75

around its circumference, a curling groove in the larger curling ring and extending substantially half way around its circumference, said thread and said groove being oppositely disposed, and said curling ring having a circumferentially cut-out portion disposed oppositely to said groove.

3. A machine for threading and beading metal caps, including rotatable male and female chucks, said chucks being relatively movable laterally into operative position, the male chuck receiving the cap blank, the female chuck being of greater diameter than the male chuck, said female chuck being threaded throughout substantially one half of its circumference and provided with a curling groove throughout substantially the remainder of the circumference, said thread and groove being in different planes.

4. A machine for threading and beading metal caps, including rotatable male and female chucks, the male chuck receiving the cap blank, the female chuck being of greater diameter than the male chuck, said female chuck being threaded throughout substantially one half of its circumference and provided with a curling groove throughout substantially the remainder of the circumference, said thread and groove being in different planes.

5. A machine for threading and beading metal caps, including rotatable male and female chucks, the male chuck receiving the cap blank, the female chuck being of greater diameter than the male chuck, said female chuck including a threading ring and a curling ring arranged side by side, said threading ring being threaded through only a portion of its circumference, said curling ring having a groove extending through only a portion of its circumference, the active portions of said rings arranged in sequence.

6. A machine for threading and beading metal caps, including rotatable male and female chucks, the male chuck receiving the cap blank, the female chuck being of greater diameter than the male chuck, said female chuck including a threading ring and a curling ring arranged side by side, said threading ring being threaded through only a portion of its circumference, said curling ring having a groove extending through only a portion of its circumference, the active

portions of said rings arranged in sequence, and means for reversing the sequence.

7. A machine for threading and beading metal caps, including male and female chucks rotatable about substantially parallel axes, the male chuck receiving the cap blank, the female chuck being of greater diameter than the male chuck, said female chuck including a threading ring and a curling ring arranged side by side, the threading ring having a thread extending about its circumference a sufficient distance to form the thread in the cap, the curling ring having a groove extending about its circumference a distance sufficient to form a curled bead around the edge of the cap, the threading ring and curling ring being so positioned radially that one will not become active until the other has substantially completed its operation.

8. A machine for threading and beading caps, including male and female chucks rotatable about substantially horizontal parallel axes, said chucks being movable laterally relatively into cooperative relation, the male chuck provided with knurling, threading and curling rings, the female chuck provided with knurling, threading and curling rings of greater diameter than those of the male chuck, said rings being arranged side by side on each chuck, the threading ring of the female chuck having a thread extending through substantially one half of its circumference, the curling ring having a circumferential cut-out portion extending through that portion of its circumference corresponding with the threaded portion of the threading ring, and a curling groove extending through the remainder of the circumference of the curling ring.

9. A machine for threading and beading metal caps, including rotatable male and female chucks, the male chuck receiving the cap blank, the female chuck being of greater diameter than the male chuck; said female chuck being threaded through only a portion of its circumference and provided with a curling groove throughout only a portion of its circumference, the threading portion and the curling portion arranged in sequence.

BERT J. HUNTSMAN.
